UNITED STATES PATENT OFFICE

154,255

DESIGN FOR A COMBINED TOOTHBRUSH, CONTAINER AND HOLDER

William B. England, Oakland, Calif., assignor to
Charles D. Beatie, San Francisco, Calif.

Application May 19, 1947, Serial No. 139,135

Term of patent 3½ years

(Cl. D9—2)

To all whom it may concern:

Be it known that I, William B. England, a citizen of the United States, residing at 280 Ridge-way Street, Oakland, county of Alameda, State of California, have invented a new, original, and ornamental Design for a Combined Tooth Brush, Container and Holder, of which the following is a specification, reference being had to the accompanying drawing, forming a part thereof.

Fig. 1 is a side elevation of a combined tooth brush, container and holder, embodying my new design;

Fig. 2 is a front end view of Fig. 1;

Fig. 3 is a top plan view of Fig. 1;

Fig. 4 is a side elevation of Fig. 1, the cap being removed;

Fig. 5 is a rear end view of Fig. 4;

Fig. 6 is a top plan view of Fig. 4;

Fig. 7 is a side elevation of Fig. 4 with the tooth brush ready for use; and

Fig. 8 is a top plan view of Fig. 7.

Fig. 9 is a perspective view of the removed cap.

I claim:

The ornamental design for a combined tooth-brush, container and holder, as shown.

WILLIAM B. ENGLAND.
